CONTAINER

Harry W. Jones, Knoxville, Tenn., assignor to Dempster Brothers, Incorporated, Knoxville, Tenn., a corporation of Tennessee

Application September 2, 1953, Serial No. 378,020

6 Claims. (Cl. 214—317)

This invention relates to an improved container of the type adapted to be elevated along an upright skid frame or the like to a transporting and/or dumping position.

By way of example, containers of the type to which the invention relates are used in conjunction with transporting and dumping equipment such as illustrated by U. S. Patent No. 2,179,779, and although the invention is not restricted to containers so used, this example will be referred to hereinafter for purposes of illustration. Such containers are elevated by lifting hooks or the like that are attachable to and detachable from suitable means such as projecting pins located on each end wall of the container approximately in the vertical center line thereof. During its elevation, movement of the container is guided and tilting and/or overturning thereof are prevented by sliding engagement of one of the container side walls with the skid frame. For transportation or storage purposes, the skid frame is then moved forwardly on its support and the elevated container lowered to rest on the support, e. g., a vehicle chassis in the example under consideration. For dumping purposes, a bail located at or near the top of said one side wall eventually reaches and engages and elevated suspension hook or its equivalent. Then the container can be dumped by tilting it about the point of attachment of the bail thereto, or by allowing a drop-bottom to open.

Under normal conditions such containers can be handled as described above without any difficulty whatsoever, as attested by the widespread use of this type of equipment. In some cases, however, it is desirable or necessary for the bail wall of the container, i. e., that side wall of the container with which the bail is associated, to be of less than the normal height for which the elevating equipment is designed. For example, it may be necessary to stow the container under a low platform or other structure, or to provide a container of special shape adapted to fit and cooperate with other devices. But reduction of the height of the bail and bail wall for such reasons can interfere seriously with the handling of the container, as explained in greater detail hereinafter, and the chief object of the present invention is to provide an improved container of relatively low bail wall height for use under such special conditions which can be handled by transporting and dumping equipment or like elevating apparatus in the normal manner and without difficulty.

Another object is to provide such a container having a bail and bail wall of variable height so that it can be lowered to meet special conditions such as mentioned above, or raised for cooperation with the transporting and dumping equipment or other apparatus of the type in question.

One embodiment of the invention has been illustrated in the accompanying drawings, but it is to be expressly understood that said drawings are for purposes of illustration only and are not to be construed as a definition of the limits of the invention, reference being had to the appended claims for this purpose.

2

In the drawings,

Figs. 1 and 2 are side views illustrating transporting and dumping equipment of the type shown in the aforesaid patent, in conjunction with a container of special shape such as to give rise to the problems mentioned above;

Figs. 3 and 4 are side views illustrating the use of a container embodying the present invention;

Figs. 5 and 6 are detail views, Fig. 5 being a section on the line 5—5 of Fig. 6, and Fig. 7 is a perspective view, of means embodying the present invention; and

Fig. 8 illustrates the use of said means in dumping the container.

Referring first to Figs. 1 and 2, the transporting and dumping equipment shown for purposes of example is of the type disclosed and claimed in the aforesaid Dempster Patent No. 2,179,779, but it will be understood that containers embodying the present invention may be used with various other types of handling equipment, either transportable or stationary. In the form shown, a vehicle chassis is indicated generally at 1, being mounted on suitable wheels including the rear wheels 2. A hoisting means in the form of a boom 3 is mounted pivotally on the chassis at 4 and is adapted to lift the container hereinafter described by suitable means such as chains 5 terminating in attaching members 6 of any suitable type. The boom 3 may be elevated by any suitable means such as a hydraulic cylinder 7 pivotally mounted at 8 on the vehicle in known manner.

At the rear of the vehicle chassis is an apron 9 which provides lateral support for the container as it leaves the ground. Above the apron, the container passes by one or more rollers 10 and then slides up an inclined frame or skidway 11. When it is desired to dump the container, it is elevated along the skidway until the bail of the container engages a suitable automatic hook 12 as hereinafter described, said hook as shown being of the type disclosed in U. S. Patent No. 2,404,830. When it is desired to transport the container, the skid frame 11 is moved forwardly by means not shown from the position of Fig. 1 to that of Fig. 2, after which the container is lowered to rest on an inclined support 13.

The container shown in Fig. 1 is of the well known drop bottom type, but it will be understood that various other types of containers can be handled on the same transporting and hauling equipment and that the invention is not restricted to drop-bottom containers. The container is elevated by means of lifting pins 14, one such pin being located approximately centrally in each end wall of the closed container. As will be understood by those familiar with this art, the drop-bottom 15 is provided with triangular wings 16 at each end and the lifting pins 14 are located at the apices of these wings so that as the chains 5 and attaching members 6 elevate the container, they also hold the drop-bottom 15 in closed position.

In the form of container chosen for illustration of the invention, a special shape is employed in which the upper right-hand portion of the container (as seen in Figs. 1 and 2) is removed, leaving a beveled or inclined wall 17, this shape being of advantage when such containers are employed with street sweepers. It will be seen accordingly that the bail 18, which is located in a recess at the top of the bail wall 19, is substantially below the level of the top edge 20 of the container as a whole. In other cases the top edges 20 of the container may be lowered to the height of the bail wall 19.

Because of this special shape, difficulties are sometimes encountered in handling such containers with transporting and dumping equipment designed to handle containers of standard sizes and shapes. For example, when the said container rests on the ground (Fig. 1), bail

18 and the top edge of the bail wall 19 are substantially below the rollers 10. As the container begins its ascent, therefore, the top edge of the bail wall 19 will sometimes catch underneath the rollers 10 with the result that the container tilts as shown in full lines in Fig. 1, instead of moving upwardly with its bail wall 19 in sliding engagement with the skid frame 11. For similar reasons, the condition shown in Fig. 2 is often encountered with such containers. As the container is lowered to or lifted from the support 13, its center of gravity may lie to the right of the lifting pins 14, causing a tendency for the container to tilt about the top edge of the bail wall 19 at the point where it engages the skid frame, the lower corner of the container swinging outwardly or to the left. In some cases this tilting may continue far enough for the container to turn completely on its side.

It will be seen that with standard containers where the wall 19 is of the same height as the upper edges 20 of the end walls, the aforesaid undesirable conditions do not occur. In Fig. 1, for example, the top edge of the bail wall 19 would then be at the rollers 10 when the container was still resting on the ground. By increasing the height of the wall 19 in Fig. 2, moreover, so that its top edge would engage the skid frame 11 at a higher point, it is evident that the tendency of the container to tilt would be substantially reduced. But projection of the wall 19 above the height shown in Figs. 1 and 2 cannot be permitted under the assumed conditions of use, whereas the transporting and hauling equipment or other elevating apparatus cannot be redesigned for such special cases without adversely affecting its use under normal conditions.

The foregoing problems are solved by the present invention in which the wall 19 of the container, with which the bail is associated, is provided with an upper bail-carrying means mounted to swing about a horizontal axis so that it can be folded down to the position of the incline 17 or if desired further to an approximately horizontal position. At the same time means are provided for locking said bail-carrying means in an upright position so that it extends above the top of the wall 19 and in effect provides an upper corner for the container such as it would have if the corner were squared out instead of being cut away along the incline 17. If the bail is of appropriate size and shape, it may itself serve as the top edge of the container, sliding in contact with the skid frame 11, in which case the bail need only be carried by a swinging arm or frame. In other cases, as where the skid frame comprises spaced uprights, the bail-carrying means may also comprise a plate or the like forming in effect an upward extension of the bail wall 19 and being located in substantially the same plane therewith.

Figs. 5-8 inclusive show the details of one embodiment of the invention of the type last referred to above. A section of the inclined wall 17 is removed to provide an opening 21, the inclined wall structure preferably being strengthened as by a pan 22, filler pieces 23, and a strap 24 or in any other suitable manner. Swingably mounted in the opening 21 is a plate section 25 which can swing from the inclined position shown in Fig. 7 to the vertical position shown in Fig. 5. This swinging plate 25 carries a suitable bail 26 and is cut away beneath the bail to provide an opening 27 that permits the operation of the hook 12 as hereinafter described. In the form shown, this bail-carrying plate is stiffened by transversely extending angles 28, 29 preferably welded thereto and by parallel ribs 30 along the edges of the opening 27 and interconnected by a transverse rib 31.

This whole structure is pivotally mounted in the opening in any suitable manner. As shown, the lower ends of the ribs 30 are formed to provide eyes through which pass suitable hinge pins 32, the pins also passing through spaced ears 33 carried by the wall 19.

Any suitable means can be provided for locking the swinging bail-carrying assembly in the upright position

shown in Fig. 5, bearing in mind that said means must have sufficient strength to withstand the requirements of service as above explained. Preferably and in the form shown, the pan 22 carries a pair of ears 34 having aligned openings to receive a pin 35 suitably connected by a chain 36 with the pan 22 in order to prevent loss. When not in use, said pin can if desired be stowed in a holder 37. An arm or strut 38 is suitably pivoted between a pair of ears 39 carried by the rib 31 by means of a pivot bolt 40. When the swinging assembly is in its inclined position shown in Fig. 7, the pin 35 being removed, the strut 38 lies between and projects beyond the ears 34 as shown in Fig. 7. When the assembly is swung to the upright position of Fig. 5, however, the pin opening in the end of the strut is drawn into alignment with the pin openings in the ears 34 whereupon the pin 35 is inserted to hold the assembly rigidly in the desired position.

Figs. 3, 4 and 8 illustrate the operation of a container of the type shown in Fig. 1, when provided with the swinging bail-carrying assembly described above. As shown in Fig. 3, the bail 26 is at the height of the rollers 10 when the container rests on the ground, and the plate 25 forms an extension of the container bail wall 19 so that the condition illustrated by Fig. 1 does not occur. Similarly in Fig. 4, the upwardly extending plate 25 and bail 26 engage the skid frame at a point in line with the top edge 20 of the container end walls and thus prevents occurrence of the objectionable condition illustrated by Fig. 2. At the same time the bail 26 is in position to function properly for dumping the container when the latter is moved upwardly to the position shown in Fig. 8. The throat 41 of the hook 12 mentioned above is masked by a slotted shuttle plate 42, the lower outer corner of which extends beyond the edge of the hook point 43 as disclosed in the aforesaid Patent No. 2,404,830. As the bail 26 slides upwardly relative to the skid frame, therefore, it first engages the inclined outer edge of the hook 43 and then engages the bottom edge of and lifts the shuttle plate 42, clearing the throat opening so that the bail can settle in the bight of the hook when the container is lowered again by the boom. Further lowering of the boom then results in opening the drop-bottom 15 in well known manner. Further elevation of the boom causes the bail 26 to move upwardly around the cam face 44, permitting the shuttle plate 42 to drop back to the position shown in Fig. 8. Upon lowering of the boom, therefore, the bail passes downwardly along the outer edge of the shuttle plate and clears the hook point 43.

It will be understood, of course, that the invention is not restricted to the details of construction set forth above, nor to the examples described by way of example, and that various details can be made in the form and arrangement of the parts without departing from its spirit. Accordingly reference should be had to the appended claims for a definition of the limits of the invention.

What is claimed is:

1. A container of the type adapted to be elevated with a wall thereof in sliding engagement with an upright frame for lateral support and having a bail associated with said wall and located near its top for engagement with an elevated suspension means, said wall having an upper bail-carrying means swingable about a horizontal axis between upright and lowered positions, and means for securing said bail-carrying means in said upright position forming an upward extension of said wall, said bail-carrying means having a portion coextensive with the portion of said wall that engages said frame and said portions having simultaneous sliding engagement with said frame.
2. A container as defined in claim 1, said bail-carrying means comprising a plate forming an extension of said wall when in said upright position, said plate having an

opening therein below the bail to receive said suspension means.

3. A container as defined in claim 1, said securing means including a strut member pivotally connected at its ends to the container body and to said bail-carrying means, at least one of said connections being detachable.

4. A container of the type adapted to be elevated with an approximately vertical wall thereof in sliding engagement with an upright frame for lateral support, said wall having an angular extension of its upper edge, bail-carrying means pivotally mounted on said container near the top of said approximately vertical wall and having a bail for engagement with an elevated suspension means, said bail-carrying means being swingable from an approximately vertical upright position to a lowered position at substantially the same angle as said extension, and means for securing said bail-carrying means in said upright position forming an upward extension of said approximately vertical wall.

5

10

15

5. A container as defined in claim 4, said angular extension having an opening therein, said bail-carrying means including a plate of substantially the same size and shape as said opening and substantially filling said opening in said lowered position.

6. A container as defined in claim 4, said bail-carrying means including a plate forming said upward extension of said bail wall when in upright position, said plate having an opening therein below the bail for receiving said suspension means.
